CLAIM

The ornamental design for a food shield bracket, as shown and described.

DESCRIPTION

FIG. 1 is a right side, top, front perspective view of a first embodiment of a food shield bracket showing the new design, a second embodiment being an opposite side bracket which is a mirror image of the first embodiment;

FIG. 2 is a right side, top, rear perspective view of the food shield bracket of FIG. 1, a second embodiment being an opposite side bracket which is a mirror image of the first embodiment;

FIG. 3 is a left side, top, rear perspective view of the food shield bracket of FIG. 1, a second embodiment being an opposite side bracket which is a mirror image of the first embodiment;

FIG. 4 is a left side, top, front perspective view of the food shield bracket of FIG. 1, a second embodiment being an opposite side bracket which is a mirror image of the first embodiment;

FIG. 5 is a top view of the food shield bracket of FIG. 1, a second embodiment being an opposite side bracket which is a mirror image of the first embodiment;

FIG. 6 is a bottom view of the food shield bracket of FIG. 1, a second embodiment being an opposite side bracket which is a mirror image of the first embodiment;

FIG. 7 left side elevation view of the food shield bracket of FIG. 1, a second embodiment being an opposite side bracket which is a mirror image of the first embodiment;

FIG. 8 is a right side elevation view of the food shield bracket of FIG. 1, a second embodiment being an opposite side bracket which is a mirror image of the first embodiment;

FIG. 9 is a rear elevation view of the food shield bracket of FIG. 1, a second embodiment being an opposite side bracket which is a mirror image of the first embodiment; and,

FIG. 10 is a front elevation view of the food shield bracket of FIG. 1, a second embodiment being an opposite side bracket which is a mirror image of the first embodiment.

1 Claim, 10 Drawing Sheets
